MAILBOX

Herbert Gosweiler, Stratford, Conn., assignor to Etched Products Corporation, Long Island City,
N. Y., a corporation of New York

Application December 1, 1951, Serial No. 17,589

Term of patent 14 years

(Cl. D74—9)

To all whom it may concern:

Be it known that I, Herbert Gosweiler, a citizen of the United States of America and resident of Stratford, in the county of Fairfield and State of Connecticut, have invented a new, original, and ornamental Design for a Mail Box, of which the following is a specification, reference being had to the accompanying drawing, forming part hereof, in which:

Fig. 1 is a front perspective view of a mail box in a closed condition, showing my new design;

Fig. 2 is a front perspective view of the opposite end of that shown in Fig. 1 and with the lid opened; and

Fig. 3 is an end elevation of the same.

I claim:

The ornamental design for a mail box, as shown.

HERBERT GOSWEILER.
